UNITED STATES PATENT OFFICE.

EDMUND SCHERL, OF NEW YORK, N. Y.

AUTOMATIC VALVE-CONTROLLING DEVICE.

Application filed November 19, 1924. Serial No. 750,741.

To all whom it may concern:

Be it known that I, EDMUND SCHERL, a citizen of the United States, residing at New York, in the county of the Bronx and State of New York, have invented certain new and useful Improvements in Automatic Valve-Controlling Devices, of which the following is a specification.

This invention relates to devices for automatically operating the valve of heating appliances and has as its principal object the provision of means for closing the gas inlet valve of heating apparatus, as stoves and the like, when the same has attained a definite degree of heat.

Another purpose is to provide a device, operated by the known expansion of metals for actuating a supply valve into a closed position.

A further aim is to provide such devices in forms that may be readily applied to existing structures as well as at their initial installation.

These several aims and objects are accomplished by the operation of well known physical laws as applied to a novel construction and arrangement of parts herein-after more fully described and illustrated in the accompanying drawing, forming an essential part of this disclosure, and in which:—

Figure 1 is a vertical sectional view of a heater showing the application of the embodiment of the invention.

Figure 2 is a side elevational view of the same, parts being broken away.

Figure 3 is a similar view of the same in another position.

Figure 4 is an enlarged transverse partial sectional view of portions thereof.

Fig. 5 is a detail view of a part thereof.

Referring more in detail to the drawing, which represents a conventional type of gas heater or stove, the numeral 10 designates a base on which is a stand 11 having a raised bead 12, circumjacent a level bottom 13.

A hollow cylindrical body 14 rests on the base, within the bead 12 and at the top of the body is a cap ring 15 having a bead 16 fitting the cylinder and a raised bead 17 which acts as a guide for an ornamental cover 18 provided with a knob 19 for convenience in removal.

The ring 15 is provided with a nest of plates 20 which upon being removed permits placing of vessels of various kinds di-

rectly over the stove to be subjected to its heat.

A supply of gas is delivered through the pipe 22 and controlled by the valve 23, the operation of which will be again referred to. A continuation of the pipe 22 is provided with an elbow 24 in which is a stand pipe 25 passing through the stand flooring 13 to which it is firmly secured by the clamp nuts 26, and is provided with a cap 27.

A helically coiled burner pipe 28 is connected at its ends near the top and bottom respectively of the stand pipe, in open communication therewith and a plurality of outlets or burner openings 29 are formed in the coil through which the gas passes into the chamber 30 in the body 14, these jets being ignited when in operation.

Rigidly attached to the exterior of the body 14, to extend at a spaced distance therefrom, is a vertical bracket 31 of any desired configuration, this bracket carrying the valve actuating parts now to be described.

A helically coiled wire 32 is disposed transversely across the chamber 30, one end of the coil having a fixed collar 33 abutting the body wall, the extending end of the wire being provided with a nut 34 by which the collar is firmly clamped and prevented from turning.

The other end of the wire passes freely out through an opening in the body to another larger fixed collar or flange 35 which abuts the inner side of a portion of the bracket 31, through which a shouldered portion 36 of the coil passes to rotate therein, a continuation 37 of the coil being fixed in the hub of a lever 38, and clamped rigidly by the nut 39 on the threaded extremity 40 of the coil.

Pivotedly connected with the outer, free end of the lever 38 is a pitman or link 41, its lower end being pivotally engaged with an arm 42 of a bell-crank lever, pivoted at 43 to the bracket 31, the other arm 44 of the bell-crank lever being cross-forked.

These forks engage a pin 45 fixed in a spindle 46 slidably in the extreme lower portion of the bracket 31, transversely of the stove.

Fixed on the stem of the valve 23 is a lever 48, one end of which is shaped for hand actuation and the other pivotally engaged with a link 49 pivoted at its opposite end to a plate link 50 and suspended by a

coiled tension spring 51 carried by an arm of the bracket 31.

A capped tubular extension 52 of the bracket 31, carries a plunger 53 in register with the spindle 46, the plunger being of larger diameter than the spindle and having a bevelled inner end adapted to enter an opening 54 in the plate link 50 due to the effect of a compression spring 55 in the extension 52.

In operation, the gas jets 29 being lit and the valve opened by manually depressing the lever 48, the stove will be heated to the required extent.

Should the temperature rise above such degree, the wire coil 32 will expand, and as one end is firmly anchored, the other end will twist in the manner of a torsion spring, actuating the lever 38, pitman 41 and bell-20 crank lever, forcing the spindle 46 against the end of the plunger, displacing it from the opening 54, whereupon the spring 51 acts through the links 54 and 49 to move the lever 48 so as to close the passage 25 through the valve 23 and cut off the gas supply.

Obviously the coil 32 acts as a thermostatic element and takes considerable time for its operation, during which the stove 30 may be used as desired.

To relight, the valve is again opened and a flame applied in any convenient manner.

Having thus described my invention and

set forth the manner of its construction, application and operation, what I claim as new and desire to secure by Letters Patent, is:—

1. The combination with a gas heater and a supply pipe leading thereto, said pipe being provided with a valve, a lever for operating said valve, a spring drawn link acting on said lever to close the valve, a plunger engaging said link to retain the valve open, a thermostatic torsion element in said heater, and means actuated by said element upon the accession of heat to displace said plunger and permit the valve to close.

2. The combination with a gas heater and a supply pipe leading thereto, said pipe being provided with a valve, a lever for operating said valve, a spring drawn link acting on said lever to close the valve, a plunger engaging said link to retain the valve open, a thermostatic torsion element in said heater, one end of said element being fixed and the other rotatable, link connected levers movable by the action of said member, and a sliding spindle operated by said levers to displace said plunger whereby the link is freed and the spring permitted to close said valve.

In witness whereof I have affixed my signature.

EDMUND SCHERL.
